(57) **CLAIM**

The ornamental design for a latch, as shown and described.

DESCRIPTION

FIG. 1 is a top perspective view of the latch according to a first embodiment of our new design;

FIG. 2 is a front view thereof;

FIG. 3 is a rear view thereof;

FIG. 4 is a first side view;

FIG. 5 is a second side view thereof;

FIG. 6 is a top plan view thereof;

FIG. 7 is a bottom plan view thereof;

FIG. 8 is a bottom perspective view thereof; and.

FIG. 9 is a rear perspective view thereof with select components removed to provide an unobstructed rear view.

FIG. 10 is a top perspective view of the latch according to a second embodiment of our new design;

FIG. 11 is a front view thereof;

FIG. 12 is a rear view thereof;

FIG. 13 is a first side view;

FIG. 14 is a second side view thereof;

FIG. 15 is a top plan view thereof;

FIG. 16 is a bottom plan view thereof;

FIG. 17 is a bottom perspective view thereof; and,

FIG. 18 is a rear perspective view thereof with select components removed to provide an unobstructed rear view. The broken lines are for illustrative purposes only and form no part of the claimed design.
